UNITED STATES PATENT OFFICE.

WILLIAM J. MONSTER, OF KNOXVILLE, IOWA.

HEN'S NEST.

1,202,874.

Specification of Letters Patent.

Patented Oct. 31, 1916.

Application filed June 5, 1916. Serial No. 101,800.

To all whom it may concern:

Be it known that I, WILLIAM J. MONSTER, a citizen of the United States, residing at Knoxville, in the county of Marion, State 5 of Iowa, have invented certain new and useful Improvements in Hens' Nests; and I do hereby declare the following to be a full, clear, and exact description of the invention, such as will enable others skilled 10 in the art to which it appertains to make and use the same.

This invention relates to hens' nests.

The object of the invention is to provide a hen's nest embodying two compartments 15 and a hinged cover or lid for each compartment and means whereby said lids may be connected to be operated in unison.

A further object of the invention is to provide a hen's nest of the type named which 20 will be so shaped when the lids or covers are closed that it will be impossible for the fowl to roost on or in the nest.

With the above and other objects in view the invention consists in the details of construction and in the arrangement and combination of parts to be hereinafter more fully described and particularly pointed out in the appended claim.

In describing the invention in detail 30 reference will be had to the accompanying drawings wherein like characters of reference denote corresponding parts in the several views, and in which—

Figure 1 is a front view of a nest constructed in accordance with the invention with the lids or covers in upright or open position; Fig. 2, a side view of what is shown in Fig. 1; Fig. 3, a view similar to Fig. 2 with the covers or lids in closed position; Fig. 4, a section on the line 4—4 of Fig. 3; Fig. 5, is a plan view of what is shown in Fig. 3, and Fig. 6, a section on the line 6—6 of Fig. 5.

Referring to the drawings the improved 45 nest comprises a body portion A including a bottom 10, side members 11 and 12, a rear member 13, a front member 14 of less height than the rear member, and a top member 15 which latter is formed integral with the 50 rear member 13. The body A is divided

into independent compartments 16 and 17 by means of a partition 18 which connects the front and rear members. It will be noted that the top member 15 extends only a slight distance toward the front member 14 and hinged to the forward edge of the top member 15 are lids or covers 19 or 20 which are adapted to close respectively the compartments 16 and 17. Mounted on the cover 19 and slidably in suitable guides 21 is a latch 22 which can be moved into interlocking relation with respect to a keeper 23 carried by the cover 20 and whereby the covers may be secured together for simultaneous movement. Each cover 19 and 20 has secured thereto adjacent its outer side edge a bracket 24 and pivoted to these brackets respectively are arcuate arms 25 and 26 having their outer edges provided with notches 27. Mounted on the side member 11 are spaced eye members 28 between which the arm 25 is slidably engaged. The lower eye member 28 is adapted to engage in the notches 27 of the arm 25 to secure the cover 19 in a desired position. The free end 70 of the arm 25 is enlarged by rolling same as at 29 and this enlarged end is adapted under normal conditions to engage a cotter 30 detachably mounted in the eye members 28. By removing the cotter 30 the cover 80 19 can be operated to full open position. Likewise there is pivoted to the bracket 24 carried by the cover 20 an arcuate arm 26 provided with notches 32. This arm 26 is slidable between eye members 33 mounted 85 on the side member 12, the notches 32 being adapted to receive the lower eye member 33 to support the cover 20 in a desired position. The free end of the arm 26 is also enlarged and is adapted to engage a removable cotter 34 carried by the eye members 33 to prevent movement of the cover 20 to full open position. The side members 11 and 12 are provided respectively with air openings 35.

What is claimed is—

A hen's nest comprising a body having an opening in its top and including a bottom, side members, front and rear members, a partition dividing the body into inde- 100

pendent compartments, a pivoted cover for closing each compartment, means for locking the covers together for movement in unison, an arm pivoted to each cover, and means carried by the side members, and detachably interlocking with said arms to hold the covers in an adjusted position.

In testimony whereof, I affix my signature, in the presence of two witnesses.

WILLIAM J. MONSTER.
